Primary Examiner — Barbara Fox*Assistant Examiner* — Kimberly Barnes(74) *Attorney, Agent, or Firm* — Fitch, Even, Tabin & Flannery, LLP(57) **CLAIM**

We claim the ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a second embodiment thereof. The broken lines shown in the drawings illustrate portions of the display screen or portion thereof with graphical user interface that form no part of the claimed design.
